JOHN E. SMITH, OF WATERBURY, CONNECTICUT.

Letters Patent No. 102,982, dated May 10, 1870.

IMPROVEMENT IN HAT-CHECKS.

The Schedule referred to in these Letters Patent and making part of the same.

To all whom it may concern:

Be it known that I, JOHN E. SMITH, of Waterbury, in the county of New Haven and State of Connecticut, have invented a new Improvement in Hat-Check; and I do hereby declare the following, when taken in connection with the accompanying drawings and the letters of reference marked thereon, to be a full, clear, and exact description of the same, and which said drawings constitute part of this specification, and represent in—

Figure 1 a perspective view of the hook when not in use;

Figure 2, a side view illustrating the operation; and in

Figure 3, the check detached.

This invention relates to a device for checking hats at hotels and other places where hats of numerous persons are necessarily deposited together, the object being to secure a mark to the hat, the duplicate of which the wearer may take when he leaves his hat; and

The invention consists in a spring clamp combined with two checks, duplicate of each other, one of which aids in securing itself to the hat, the other to be taken by the wearer.

A A are two parts of a clamp, formed from sheet metal, doubled at *a*, and their two ends, *b*, curved, but so that the two may be brought together, as denoted in broken lines, fig. 2, the elasticity of the parts, however, tending to separate the two ends.

B is the permanent check, and is made to move up and down, as from the position in fig. 2 to that in broken lines in the same figure, which movement forces the two ends tightly together.

The other check C is a duplicate, numbered the same as the permanent check, here numbered 5. This may be perforated with a recess, D, so as to pass on over the two ends, and be held, as in fig. 1, by the extension of the two ends, but so that by compressing the ends together the check C may be removed, or it may be passed on over the other end.

For convenience of suspension, I arrange a ring, E, at the doubled end of the clamp.

When a gentleman desires to leave his hat, the person in charge takes one of these devices, gives to the wearer the duplicate C, and secures the original to the hat by pressing it down, and clamping the two ends upon the rim or other portion of the hat.

I claim as my invention—

The clamping device A A, constructed as described, in combination with the check B, which serves as a means for securing the clamp and its duplicate C, constructed so that when not in use it may rest upon the clamp, and when required for use be easily detached therefrom.

JOHN E. SMITH.
